UNITED STATES PATENT OFFICE.

DAVID WENTWORTH, OF GARDINER, MAINE, ASSIGNOR TO THE WENTWORTH SPRING AND AXLE COMPANY, OF SAME PLACE.

DESIGN FOR AN AXLE-NUT.

SPECIFICATION forming part of Design No. 14,089, dated July 10, 1883.

Application filed April 27, 1883. Term of patent 7 years.

To all whom it may concern:

Be it known that I, DAVID WENTWORTH, of Gardiner, in the county of Kennebec and State of Maine, have invented certain new and 5 useful Improvements in Designs for Axle-Nuts; and I do hereby declare the following to be a full, clear, and exact description of the invention, such as will enable others skilled in the art to which it appertains to make and 10 use the same.

In the accompanying drawing, Figure 1 is a view in perspective of an axle-nut embodying my newly-invented design.

The leading feature of my design is a square 15 nut having a disk in relief appearing upon its outer face.

The axle-nut consists of a sand-guard, A, provided with an annular flange, B, and of a square nut, C, having a disk, D, upon its outer face.

20

I claim—

The design for the axle-nut herein shown and described, the same consisting of a square nut having a disk in relief appearing upon its outer face, sand-guard, and the annular flange. 25

In testimony whereof I have signed this specification in the presence of two subscribing witnesses.

DAVID WENTWORTH.
